UNITED STATES PATENT OFFICE.

EDWIN O. KRENTLER, OF DETROIT, MICHIGAN, ASSIGNOR TO KRENTLER-ARNOLD HINGE LAST COMPANY, OF DETROIT, MICHIGAN, A CORPORATION.

HINGED LAST.

No. 902,303.

Specification of Letters Patent.

Patented Oct. 27, 1908.

Application filed February 10, 1908. Serial No. 415,046.

To all whom it may concern:

Be it known that I, EDWIN O. KRENTLER, a citizen of the United States, and resident of Detroit, in the county of Wayne and State of Michigan, have invented an Improvement in Hinged Lasts, of which the following description, in connection with the accompanying drawings, is a specification, like letters on the drawings representing like parts.

My invention has for its object an improvement on the last construction of my application Serial No. 409,262, filed January 4, 1908, whereby much greater strength and stability of the last are secured and the same is automatically locked in lengthened position and readily unlocked for shortening.

The constructional details of the invention will be pointed out more at length in the course of the following description, taken with reference to the accompanying drawings, in which I have shown a preferred embodiment of the invention.

In the drawings, Figure 1 represents my improved last in side elevation, part of the side being broken away to show the internal construction; Fig. 2 is a top plan view thereof; and Figs. 3 and 4 are fragmentary sectional views of slightly modified constructions.

In the preferred construction herein shown, the fore-part 1 and heel-part 2 are severed along a broken line 3, 4, 5, 6, 7, the upper forward end of the heel-part being preferably cut away at 8, and said last parts are joined by a hinge or hinge-plate 9 pivoted on a pin or rivet 10 at its forward end and on a heavy rivet 11 at its rear end said severing on the broken line of cut and said pivoted link co-operating to permit pivotal movement of the two last-parts with relation to each other when in a shoe. At its front end the link or hinge-plate 9 is provided with a locking finger or latch 12 pivoted thereto at 13 and having a shoulder 14 overhanging a locking pin 15 extending across the kerf 16 in which the hinge parts are mounted in the forepart, said finger being normally pressed toward the back of the last by a spring 17. The line of severance is such that instead of having simply a slight overhang or engaging corner as in my above mentioned application, I have provided a horizontal abutment or ledge between the points 5 and 6, so that when the

last is in lengthened position great strength is provided (especially when the location and arrangement of the heavy pins or rivets 10, 11 and plate 9, and the inclined contacting walls of the last between the points 4 and 5 are taken into account) to resist leveling pressures, the last then being bottom up, and when the last is in shortened position great stability is insured by the engagement of the lower front corner of the heel-part 65 with the overhanging abutment 5, 6 as shown in dotted lines Fig. 1. Also the special arrangement of locking means co-operates in imparting great strength and aids in preventing splitting tendencies, etc. 70

Instead of riveting the parts 9 and 12, they may be pivotally secured together in any other manner, as for instance as shown in Fig. 3, where the pivoting of the parts is secured by a circular projection 18 on the hinge-plate, partially embraced by a complementary recess 19 on the finger 12. This avoids the separate riveting and yet brings the finger 12 into the same vertical plane as the hinge-plate 9 for distributing the pulling strain with the greatest strength and to the best advantage the same as when the two parts are halved together and riveted as shown in Fig. 2. Also, when a positive locking of the last-parts is not desired, but 80 it is desired to lock the last-parts by merely a retarding or strong frictional holding of the last-parts, the shoulder 14 is omitted and the locking finger 12 is cut away, as indicated at 20, thereby accomplishing the result desired. 85

My last is primarily intended for a first last, in which case it starts in a shoe, in its lengthened position, and is held rigid by the peculiarities of the cut or line of severance 95 and by the lock, and in this position goes through the various machines, such as pulling-over machine, heeler, and leveler, after which the locking finger or latch 12, which has previously prevented any possible movement of the last-parts, is pushed forward against the action of spring 17 until the shoulder 14 escapes from the pin 15, thereby permitting the last to turn up into shortened position and be released from the shoe. 100

For relasting purposes, the last is normally in the position shown in dotted lines, bottom up, supported in usual manner at its heel or a relasting jack, and the shoe is forced over the toe and back to the heel, 110

the tendency of the last to move unexpectedly into lengthened position being prevented by the engagement of the corner of the heel at the front bottom edge thereof 5 with the overhanging inclined wall or secant face of the forepart. When the shoe has been forced fully over the last, the latter and the supported shoe are removed from the jack and the heel-part is shoved down into 10 the counter portion of the shoe, the locking device automatically holding the parts in lengthened position. Not only is the locking of the last rendered entirely automatic by pivoting the locking finger to the end of 15 the hinge-plate which projects beyond its pivot 10, but this location of the locking device whereby it is embraced by the walls of the kerf 16 makes the construction very firm and the movement precise and easy to operate 20 from the outside. A still more important result of this construction is that any movement tending to shorten the last results in a pulling strain of the pins 10 and 15 toward each other, thereby binding the 25 last together, as distinguished from tending to split the last, which latter has been a serious disadvantage of the common locking means for this general type of last, in which the locking device has been so constructed 30 as to resist shortening movement by an outward or upward pressure or strain instead of the herein downward or inward strain.

As already intimated, I do not intend to limit my invention to the precise construction shown, as various modifications and rearrangements of parts may be resorted to within the spirit and scope of my invention as defined in the appended claims.

The last herein shown is one form or embodiment of a divided last whose heel-part has a combined pivotal and sliding-swing movement with relation to the forepart, the same not being herein broadly claimed, but claimed in my copending application Serial 45 No. 421,521, filed March 16, 1908, and that particular form in which the link is apertured at its opposite ends, which are mounted snugly on transverse pivot pins for pivotal movement only whereby the pivot pins 50 are maintained in all positions at the same distance apart, although likewise herein shown, is not herein claimed, but is claimed in my copending application Serial No. 409,262, first mentioned above. The present 55 case is limited to the particular line of cut which includes the rearward extending abutment with its horizontally overlapping wall or surface, and to the provision of locking means mounted on or movable with or actuated by the movement of the link or hinge-plate, as hereinafter more particularly defined, and I wish it further understood that in the claims I intend the word "locking means" or "locking finger" to include the 60 frictional locking as by the inclined surface 65

20 as well as the more positive locking by the shoulder 14, unless a given claim is restricted to the latter locking-shoulder by its express terms. I refer to the claims for a definite statement of the features to which this case is restricted, and I have referred to my two other copending cases in order that it may be understood why certain features herein shown are not herein claimed.

Having described my invention, what I 75 claim as new and desire to secure by Letters Patent, is:

1. A divided last, comprising a forepart and heel-part, separated by a broken line of cut and provided with connecting means, 80 permitting each of said parts to have a pivotal movement with relation to the other when in a shoe, said two last-parts being severed by a line of cut affording a corner at the front bottom edge of the heel-part 85 and an abutment extending approximately horizontally rearwardly from the rear bottom end of the forepart in position to engage and support said corner when the last is shortened. 90

2. A divided last, comprising a forepart and heel-part separated by a broken line of cut and provided with a single connecting hinge-plate pivoted adjacent its opposite ends in and to the respective last-parts, permitting each of said parts to have a pivotal movement with relation to the other when in a shoe, said two last-parts being severed by a line of cut affording a corner at the front bottom edge of the heel-part and an abutment 95 extending approximately horizontally rearwardly from the rear bottom end of the forepart in position and operating to engage and support said corner when the last is shortened. 100

3. A divided last, having a separate forepart and heel-part, connecting means permitting one part to swing on the other, including a horizontal pivot in one of said parts, a locking finger pivoted on said connecting means within said pivot-containing last-part beyond said pivot, and stationary means to be engaged by said locking finger to lock the last in lengthened position. 110

4. In a last, a forepart and heel-part, a hinge-plate pivoted at its opposite ends in said respective last-parts, a locking finger mounted on said hinge-plate and movable therewith eccentrically about the adjacent pivot, and means coöperating with said finger to lock the last in lengthened position. 115

5. In a last, a forepart and heel-part, a hinge-plate at its opposite ends in said respective last-parts, a locking finger mounted on said hinge-plate and moved in a direction opposite to the movement of the heel-part, by the swinging of said hinge-plate on its pivot in the last-part containing said finger, and means coöperating with said finger to lock the last in lengthened position. 120 130

6. In a divided last, a forepart and heel-part, a connecting link pivoted at its opposite ends in the respective last-parts, and automatic locking means supported and carried by said link and actuated by the movement of said link to last-lengthened position to lock the last in said lengthened position.

7. In a last, a forepart and heel-part, a hinge-plate pivotally connecting said last-parts, a locking finger mounted on the forward end of said hinge-plate beyond the pivot thereof in the forepart and extending upwardly in said forepart, said finger having a locking shoulder, and a transverse pin in said forepart to be engaged by said shoulder when the last is in lengthened position.

8. In a last, a forepart and heel-part, a hinge-plate pivotally connecting said last-parts, a locking finger mounted on the forward end of said hinge-plate beyond the pivot thereof in the forepart and extending upwardly in said forepart, said finger having a locking shoulder, a transverse pin in said

forepart to be engaged by said shoulder when the last is in lengthened position, and a spring normally tending to maintain said pin and finger in locking engagement.

9. In a last, a forepart and heel-part, a hinge-plate pivotally connecting said last-parts, a locking finger mounted on the forward end of said hinge-plate beyond the pivot thereof in the forepart and extending upwardly in said forepart, said finger having a locking shoulder, and a transverse pin in said forepart to be engaged by said shoulder when the last is in lengthened position, said finger extending above the last in position to be engaged externally of the last for unlocking the latter.

In testimony whereof, I have signed my name to this specification, in the presence of two subscribing witnesses.

EDWIN O. KRENTLER.
